F. VOGLHUT
FILAMENT HOLDER TO BE USED IN CONNECTION WITH THE
REGENERATING OF ELECTRIC INCANDESCENT LAMPS
Filed Dec. 15. 1921

Inventor:
Franz Voglhub,
by Byers, Townsend & Brickenstein,
Atty.

UNITED STATES PATENT OFFICE.

FRANZ VOGLHUT, OF AUGSBURG, GERMANY.

FILAMENT HOLDER TO BE USED IN CONNECTION WITH THE REGENERATING OF ELECTRIC INCANDESCENT LAMPS.

Application filed December 15, 1921. Serial No. 522,696.

To all whom it may concern:

Be it known that I, FRANZ VOGLHUT, a citizen of the German Republic, residing at Augsburg, Germany, have invented certain new and useful Improvements in Filament Holders to Be Used in Connection with the Regenerating of Electric Incandescent Lamps, of which the following is a specification.

10 This invention relates to the renewal of incandescent lamps.

The operation of replacing the filament in lamps in which the filament holder arms terminate in an eyelet, is a tedious and difficult task.

It is the object of this invention to avoid the inconvenience just referred to.

For a full understanding of the invention reference is made to the accompanying drawing.

The lamp shown represents that type in which the arms *a* terminate in an eyelet *b* through which the filament is threaded.

To facilitate the insertion of the new filament *f* through the hole *L* at the tip of the lamp, I propose to bend the arms *a* intermediate the eyelet *b* and the glass rim *c*, preferably close to the former. The bending oper-

ation may be carried out by a tool of suitable construction well known in the art, the tool 30 being passed through the hole *L*. The new filament *f* thus may be readily wound in zig-zag shape as before, but instead of being threaded through the eyelets, the filament is held in the recesses formed by the upwardly 35 extending bends *d*.

I claim:

1. In the operation of renewing incandescent lamps in which the filament holder arms terminate in an eyelet, the step which consists 40 in bending the arms adjacent the eyelet to define recesses for the reception of a filament.

2. In the operation of renewing incandescent lamps in which the filament holder arms terminate in an eyelet, the steps which consist 45 in bending the arms adjacent the eyelet to define recesses for the reception of a filament and passing the new filament into the said recesses.

In testimony whereof I affix my signature 50 in presence of two witnesses.

FRANZ VOGLHUT.

Witnesses:

BERTHOLD MONASCH,
GERTRAUDE BACHMAN.
